UNITED STATES PATENT OFFICE

156,689

FLOOR POLISHER

**Kenneth C. Atkin, Muskegon, Mich., assignor to
Clarke Sanding Machine Company, Muskegon,
Mich, a corporation of Michigan**

Application June 26, 1948, Serial No. 147,227

Term of patent 14 years

(Cl. D9—2)

To all whom it may concern:

Be it known that I, Kenneth C. Atkin, a citizen of the United States, residing at Muskegon, in the county of Muskegon and State of Michigan, have invented a new, original, and ornamental Design for a Floor Polisher, of which the following is a specification, reference being had to the accompanying drawings, forming a part thereof.

In the drawings:

Figure 1 is a front perspective view of a floor polisher, showing my new design;

Figure 2 is a side elevational view thereof; and
Figure 3 is a top plan view thereof.

I claim:

The ornamental design for a floor polisher, as shown.

KENNETH C. ATKIN.
